UNITED STATES PATENT OFFICE.

IRA ORVILLE WRIGHT, OF BALTIMORE, MARYLAND, ASSIGNOR TO FARLOW DRAFT GEAR CO., OF BALTIMORE, MARYLAND.

DRAFT AND BUFFING GEAR FOR CARS.

No. 846,374.

Specification of Letters Patent.

Patented March 5, 1907.

Application filed January 10, 1907. Serial No. 351,668.

To all whom it may concern:

Be it known that I, IRA ORVILLE WRIGHT, a citizen of the United States, residing at Baltimore city, State of Maryland, have invented new and useful Improvements in Draft and Buffing Gear for Cars, of which the following is a specification.

My invention relates to draft and buffing gear for cars, and has for its object the provision of certain improvements upon the gear disclosed in Letters Patent to Wright, Stem, and Farlow, under date of September 22, 1903, and numbered 739,769.

The invention consists in certain novelties of construction and combinations of parts hereinafter set forth and claimed.

The accompanying drawings illustrate two examples of the physical embodiment of the improvements constructed according to the best modes I have so far devised for the practical application of the principle.

Figure 1 is a vertical longitudinal section of Fig. 2, taken in a plane at one side of the draw-bar and follower-blocks. Fig. 2 is a half top plan view and a half horizontal sectional view through the follower-blocks and part of the draw-bar. Fig. 3 is a cross-section taken on line *x x* of Fig. 2. Fig. 4 illustrates the second example by a view similar to Fig. 2.

Referring to Figs. 1, 2, and 3, the numeral 1 designates the center sills of the car, being in this instance steel channel-beams; 2, the draft-sills or supports of Z shape in cross-section and secured to the center sills by rivets; 3, the end sill; 4, the body-bolster of any approved type; 5, a hole in the end sill for the passage of the draw-bar; 6, two rear slots in the web of each draft-sill or support, both being of substantially the same dimensions; 7, front elongated slots in each draft-sill or support; 8, the cheek-plates, each being cast with slots corresponding to the slots in the draft-sills and with bosses which enter the slots in said sills, the said plates being secured in place by rivets, as shown; 9, the draw-bar with a coupler-head outside the end sill; 10, a horizontal slot in the draw-bar; 11, an opening at the rear end of the draw-bar; 12, the front and rear follower-blocks of identical construction; 13, projecting lugs one at the smaller end of each block; 14, two projecting lugs at the larger

end of each block which retain the springs in their proper positions; 15, horizontal slots through the blocks; 16, a plano-convex casting at the rear end of the rear follower-block, the same being provided with a hole to receive a lug 13 of a follower-block; 17, two coil or helical springs located, as shown, in a vertical plane between the blocks; 18, keys consisting of flat metallic bars, each tapered at one end; 19, two draft-links, located as shown and united integrally or otherwise at their rear ends to form a U-shaped strap which bears against the plano-convex casting 16 at the end of the rear follower-block, and 20, three elongated slots in each draft-link.

It will be observed that when the parts are in their normal positions, as shown by Figs. 1 and 2, the keys pass through the draft-sills or supports, the slots in the links, and the slots in the follower-blocks and the draw-bar. The front key is located centrally of the front slots in the draft-sills or supports, and the two rear keys fit the slots so they cannot move longitudinally of the draft-sills. By reason of the elongated slots 15 in the follower-blocks, which slots are wider than the width of the keys which loosely pass through them, the front block can move rearwardly in buffing and the rear block forwardly in drawing. As the slots in the links are longer than the width of the keys, obviously in buffing the front key can move rearwardly within the slots, and in drawing the two rear elongated slots allow the links to be advanced and to move over the two rear keys.

In the first example the links do not move rearwardly at all in buffing. In the second example (shown by Fig. 4) the front key fits the front slots in the links and the other slots are elongated at the left of the two rear keys, as indicated at 21, so that the links may move rearwardly in buffing. The introduction of this slight change in the mode of operation renders it necessary to form the rear follower-block and the plano-convex casting 16 integral, as shown at 22, or to secure the plano-convex casting to the links so it will move with them. The elements of the gear in Fig. 4 are in other respects the same as those shown by the first example.

In practice slight modifications in construction may be introduced. For instance, the two links may be bent at their rear ends

2
or cast to shape and united by rivets or bolts, as shown at 23 in Fig. 4. The slot 10 in the draw-bar may also be elongated, so that when the parts are in their normal relative 5 positions the slot will extend to the dotted line 24 in Figs. 2 and 4. In this event the draw-bar in buffing can move rearwardly without imparting motion to the front key; but this construction is not as desirable as the 10 arrangements of parts shown by the two examples in full lines. In both drawing and buffing it is desirable to transmit the strains to a multiplicity of separated points or areas, thus distributing the same. In the two examples it will be seen that in both the drawing 15 and the buffing after the springs have been fully compressed the surplus energy or *vis viva* is transmitted to the draft-sills at six points or areas through the medium of 20 the three keys. This fact prevents the rupture of the gear which frequently occurs when the strains are transmitted to two points only, as in the common construction of draft-rigging.

25 The gear as shown can of course be applied to draft timbers or plates located below the plane of the center sills, and I intend to embrace such applications within the scope of the claims.

30 What I claim is—

1. The combination in a draft and buffing gear provided with supports having slots, of a coupler and draw-bar; a front slotted follower-block; a rear slotted follower-block; 35 a spring or springs between the blocks; slotted links which take the strains in drawing; and keys within the slots of the supports, links, follower-blocks, and draw-bar; the rear key being fixed in the supports, and 40 the rear follower-block being movable relative to said key in drawing.

2. The combination in a draft and buffing gear provided with supports having slots, of a coupler and draw-bar; a front slotted follower-block; a rear slotted follower-block; a spring or springs between the blocks; slotted links which take the strains in drawing; and keys within the slots of the supports, links, follower-blocks, and draw-bar; the 45 rear key being fixed in the supports, the draw-bar and front follower-block being movable rearwardly in buffing, and the rear follower-block being movable in a forward direction in drawing.

55 3. The combination in a draft and buffing gear provided with supports having slots, of a coupler and draw-bar; a front slotted follower-block; a rear slotted follower-block; a spring or springs between the blocks; slotted 60 links which take the strains in drawing; and keys within the slots of the supports, links, follower-blocks, and draw-bar; the rear key being fixed in the supports, the coupler and front follower-block being movable rear-

wardly in buffing while the links remain stationary, and the rear follower-block being movable relative to the rear key in drawing. 65

4. The combination in a draft and buffing gear provided with supports having slots, of a coupler and draw-bar; a front slotted follower-block; a rear slotted follower-block; a spring or springs between the blocks; slotted links which take the strains in drawing; and keys within the slots of the supports, links, follower-blocks, and draw-bar; the rear key 70 being fixed in the supports, the two links being united at their rear ends and engaging the rear follower-block which is movable relative to the rear key in drawing. 75

5. The combination in draft and buffing gear provided with supports having slots, of a coupler and draw-bar; a front slotted follower-block; a rear slotted follower-block; a spring or springs between the blocks; slotted links which take the strains in drawing; and keys within the slots of the supports, links, follower-blocks, and draw-bar; the rear key 80 being fixed, the two links being united at their rear ends, and a block being interposed between the rear follower-block and the 85 united ends of the links. 90

6. The combination in a draft and buffing gear provided with supports having slots, of a coupler and draw-bar; a front slotted follower-block; a rear slotted follower-block; a 95 spring or springs between the blocks; slotted links which take the strains in drawing; keys within the slots of the supports, links, and follower-blocks; and means for connecting the draw-bar with the front ends of the links; 100 the rear key being fixed in the supports, and the rear follower-block being movable over the fixed key in drawing. 105

7. The combination in a draft and buffing gear provided with supports having slots, of a coupler and draw-bar; a front slotted follower-block; a rear slotted follower-block; a spring or springs between the blocks; slotted links which take the strains in drawing; keys within the slots of the supports, links, and follower-blocks; and means for connecting the draw-bar with the front ends of the links; 110 the rear key being fixed in the supports; the draw-bar and front follower-block being movable rearwardly in buffing, and the rear 115 follower-block being movable in a front direction in drawing.

8. The combination in a draft and buffing gear provided with supports having slots, of a coupler and draw-bar; a front slotted follower-block; a rear slotted follower-block; a spring or springs between the blocks; slotted links which take the strains in drawing; keys within the slots of the supports, links, and follower-blocks; and means for connecting the draw-bar with the front ends of the links; 120 the rear key being fixed in the supports, the two links being united at their rear ends and 125

- bearing against the rear follower-block which latter is movable over the rear key in drawing.
9. The combination in a draft and buffing gear provided with supports having slots, of a coupler and draw-bar; a front slotted follower-block; a rear slotted follower-block; a spring or springs between the blocks; slotted links which take the strains in drawing; keys within the slots of the supports, links, and follower-blocks; and means for connecting the draw-bar with the front ends of the links; the two keys which pass through the follower-blocks being fixed in the supports, and the blocks being movable relative to the keys.
10. The combination in a draft and buffing gear provided with supports having slots, of a coupler and draw-bar; a front slotted follower-block; a rear slotted follower-block; a spring or springs between the blocks; slotted links which take the strains in drawing; keys within the slots of the supports, links, and follower-blocks; and means for connecting the draw-bar with the front ends of the links; the two keys which pass through the follower-blocks being fixed in the supports, the links united at their rear ends, and the slots in the blocks being longer than the width of the keys so the blocks may move relative to the keys.
11. The combination in a draft and buffing gear provided with supports having slots, of a coupler and draw-bar; a front slotted follower-block; a rear slotted follower-block; a spring or springs between the blocks; slotted links which take the strains in drawing; keys within the slots of the supports, links, and follower-block; and means for connecting the draw-bar with the front ends of the links; the two keys which pass through the follower-blocks being fixed, the blocks being movable relative to the keys, and the links slotted so as to move relative to the keys in drawing.
12. The combination in a draft and buffing gear provided with supports having slots of a coupler and draw-bar; a front slotted follower-block; a rear slotted follower-block; a spring or springs between the blocks; slotted links which take the strains in drawing; keys within the slots of the supports, links, and the follower-blocks; and means for connecting the draw-bar with the front ends of the links; the two links being united at their rear ends, and a filling-block interposed between said ends and the rear follower-block, said filling-block being provided with a recess to receive a lug upon the end of the follower-block.
13. The combination in a draft and buffing gear provided with supports having slots, of a coupler and draw-bar; a front slotted follower-block, a rear slotted follower-block; a spring or springs between the blocks; slot-
- ted links which take the strains in drawing; keys within the slots of the supports, links, and follower-blocks; and means for connecting the draw-bar with the front ends of the links; said links being united at their rear ends, the follower-blocks being of identical construction and each having a projecting lug, and a recessed casting located between the rear follower-block and the ends of the links.
14. The combination in a draft and buffing gear provided with supports having slots, of a coupler and draw-bar; two slotted follower-blocks; a spring or springs; slotted links united at their rear ends to form a U-shaped strap; keys located within the slots of the supports, follower-blocks, and links; and means for connecting the draw-bar with the links.
15. The combination in a draft and buffing gear provided with supports having slots, of a coupler and slotted draw-bar; slotted follower-blocks; a spring or springs; slotted links united at their rear ends to form a U-shaped strap, and keys within the slots of the supports, links, follower-blocks, and draw-bar.
16. The combination in a draft and buffing gear having supports with slots, of a coupler and draw-bar; two slotted follower-blocks; two keys within the slots of the supports and the slots of the follower-blocks; and a U-shaped strap connecting the coupler with the rear follower-block; said keys being tapered so that when the follower-blocks and spring or springs and one key are in place the other key can be driven into place and compress the spring or springs.
17. The combination with a draft and buffing gear having slotted supports and constructed and operating substantially as described, of a rear fixed key removable endwise from the slotted supports, and a slotted follower-block through which the key passes; the slot in the follower-block being longer than the width of the key whereby the block may move relative to the key.
18. The combination in a draft and buffing gear, operating substantially as set forth, of two fixed keys, two follower-blocks with elongated slots, a spring or springs, a draw-bar, and two links with elongated slots; said links being secured to the draw-bar, and the elongated slots allowing the said links to move relative to the keys.
19. The combination in a draft and buffing gear provided with supports having slots, of a coupler and draw-bar; two slotted follower-blocks; a spring or springs; keys located within the slots of the supports and slots of the follower-blocks, said keys being removable endwise from the said slotted supports, and said rear key being of less width than the length of the slot in the rear fol-

lower-block; and means for connecting the draw-bar with the rear follower-block.

20. The combination in a draft and buffering gear provided with supports having slots, of a coupler and draw-bar; two slotted follower-blocks; a spring or springs; keys located within the slots of the supports and slots of the follower-blocks, said keys being removable endwise from the said slotted supports, and each of said keys being of less

width than the length of the slot in the follower-block through which it passes; and means for connecting the draw-bar with the rear follower-block.

In testimony whereof I affix my signature ¹⁵ in presence of two witnesses.

IRA ORVILLE WRIGHT.
